UNITED STATES PATENT OFFICE.

CHARLES H. BOECK, OF JACKSON, MICHIGAN.

DESIGN FOR A ROLLER-BASE FOR OIL-STOVES.

SPECIFICATION forming part of Design No. 22,742, dated August 22, 1893.

Application filed May 6, 1893. Serial No. 473,304. Term of patent 7 years.

To all whom it may concern:

Be it known that I, CHARLES H. BOECK, a citizen of the United States, residing at Jackson, in the county of Jackson and State of Michigan, have invented and produced a new and original Design for a Roller-Base for Oil-Stoves, Gasoline-Heaters, &c.; and I do hereby declare the following to be a full, clear, and exact description of the invention, such as will enable others skilled in the art to which it appertains to make and use the same.

The accompanying drawing represents a perspective view of a roller base constructed in accordance with my design.

15 The leading features of the design reside in a circular or polygonal frame supported on rollers or casters, and having a tray or pan fitting over the circular or polygonal opening through the frame, together with sockets 20 on the upper surface thereof; the frame being suitably embossed or similarly ornament-

ed on its upper exposed surface to present a pleasing effect to the eye.

A, in the drawing denotes a circular or ring-frame having sockets a , a , on the upper surface thereof. The outer portion of the frame is formed with a depending rim or flange a' , encircling the inner flat or horizontal portion a^2 , and is rounded and embossed on the upper surface thereof as shown, and provided with 25 a lower scalloped edge. The frame is provided with a centrally arranged pan or tray B.

What I claim is—

The design for a roller base for oil stoves, &c., substantially as herein shown and described.

In testimony whereof I affix my signature in presence of two witnesses.

CHARLES H. BOECK.
